TRANSISTORIZED BREAKERLESS IGNITION SYSTEM

Merton I. Rosenberg, West Springfield, Mass., assignor to American Bosch Arma Corporation, a corporation of New York

Filed Dec. 18, 1959, Ser. No. 860,531
11 Claims. (Cl. 315—205)

This invention relates to a new and improved battery type ignition system for spark ignition internal combustion engines.

The principal object of the invention is to provide a new and improved ignition system of the type set forth which is relatively simple and economical in construction, yet efficient in operation.

An object of the invention is to provide a new and improved battery type ignition system which eliminates breaker or interrupter contacts and condensers and which achieves high engine efficiency through better combustion due to the ability of the system to provide and maintain optimum timing of injection firing.

Another object is to provide a new and improved battery type spark ignition system which will operate successfully on any multi-cylinder engine.

Other objects and advantages of the invention will be apparent from the following description taken in connection with the accompanying drawings, wherein the preferred forms of the invention have been set forth by way of illustration only.

Referring to the drawings:

FIG. 1 is a schematic circuit diagram of an ignition system embodying the invention;

FIG. 2 is a schematic view of a modified form of the invention;

FIG. 3 is a schematic showing a modified form of a circuit; and

FIGS. 4 and 5 are perspective views, partially in section, illustrating the adaptation of the system to the ignition distributor of an internal combustion engine.

Referring more particularly to the drawings wherein similar reference characters designate corresponding parts throughout and wherein the system has been shown as applied to an eight-cylinder engine by way of example, the system shown in FIG. 1 is a high tension system adapted for use on automotive, truck, marine engines, etc., whereas the arrangement shown in FIG. 2, which is of a much more expensive type, is intended for use on stationary gasoline, natural gas, L.P. gas engines, etc., where spark is a hazard and all spark, even on starting, is preferably eliminated.

The form of the invention shown in FIG. 1 comprises a magnetic pulse generator rotor PG which is preferably of permanent magnet material such as Alnico V magnetized properly. The rotor is in fixed relation with the engine timer shaft F and set physically in timed phase with the distributor arm D.

The pulse generator rotor PG is provided with a pair of pole shoes for each engine cylinder to be ignited, with each pair of pole shoes comprising a north and south pole which are labeled N and S, respectively, in the drawings.

The apparatus is provided with a distributor contact C for each engine cylinder and the distributor contacts C are each connected by an electrical lead L to a respective spark plug SP for each respective engine cylinder.

Adjacent the periphery of the rotor PG is provided a control coil CC in which is induced a pulsing voltage by the rotor PG.

The rotor PG is connected to the transformer TR by the lead K. The transformer TR comprises a primary P and a sectional wound secondary of the type sometimes referred to as Pie wound secondary.

2

The circuit includes the usual D.C. battery which is indicated as D.C. and the usual ignition switch which is indicated as SW.

The switching circuit comprises a power transistor T₁, which may be of the germanium or silicon type, whose emitter terminal E₁ is connected to the positive side of the D.C. source through a silicon rectifier RE in the direction shown through the D.C. source to ground. The collector terminal C₁ of the main power transistor T₁ is connected in series with the primary winding P of the transformer TR to ground. The base terminal B₁ of the power transistor T₁ is connected in series with the emitter terminal E₂ of the triggering transistor T₂. The collector terminal C₂ of the triggering transistor T₂ is connected to ground.

The base terminal B₂ of triggering transistor T₂ is connected to one side of the control coil CC through the control coil to the emitter terminal E₂ of transistor T₂ and connected across the control coil CC is a zener diode Z₁.

The secondary winding S of transformer TR is connected in parallel with the spark electrodes, one of which is at ground potential.

In the operation of the system, as the ignition switch SW is closed, the starting motor turns the engine cam 25 which, in turn rotates the pulse generator rotor PG. The magnetic rotor PG then induces a pulsing voltage in the control coil CC located in the base of the emitter circuit of the triggering transistor T₂. Thus, it is understood that the pulse is synchronized with the travel of the piston 30 in the particular cylinder which is to be fired, which synchronization is arranged so that the maximum voltage is obtained from the pulse generator at approximately the same time that the piston is at a position slightly before top dead center of its compression stroke. This causes 35 transistor T₂ to rapidly switch on which, in turn, causes transistor T₁ to rapidly switch on subjecting the primary P of transformer TR to a current transient, which in turn, causes a voltage transient in the primary which, when transformed to the secondary S, will cause the spark plug 40 to fire at the proper instant. The change in flux with respect to time, when multiplied by the inductance (Faraday's law) is such that enough voltage is available to cause the desired breakdown when transformed by the transformer TR.

45 The rectifier RE, located in the emitter circuit of the power transistor T₁, is provided to cause a constant voltage drop regardless of the current flowing through it. The resistor R₁ is provided to stabilize the power transistor and is determined by the stability factor for this transistor. The overall function of the rectifier RE and the resistor R₁ is to stabilize the circuit and provide a means of 50 reducing heat due to its own current carrying capabilities.

A resistor could replace the rectifier RE under certain conditions, but would not contribute a constant voltage 55 drop.

The zener diode Z₁ has two functions, the first of which is to limit the amplitude pulse voltage produced by the pulse generator PG and, second, to eliminate the negative half cycle of the pulse.

60 The transformer is designed so that the kick-back voltages will not exceed the collector C₁ to emitter E₁ voltage of the transistor T₁, otherwise known as the transistor punch-through voltage. The secondary of the transformer TR is designed such that the reactance (capacitive) due to the proximity of the secondary winding is reflected back as an impedance that approaches infinity or high enough so that very little of the primary current is absorbed due to this reflected impedance. This is accomplished by sectioning the secondary winding, or sometimes referred to as a pi (π) winding.

In FIG. 3, a modified form of circuit is shown in which

there is provided an energy control means which may be in the form of a variable potentiometer.

In the form of the invention shown in FIGS. 2 and 4, there is shown a system which is particularly adapted for low tension distribution for such uses as for stationary gasoline engines, natural gas engines, L.P. gas engines, etc. where spark is a hazard and no spark is desired, even for starting.

In this form of the invention the magnetic rotor PG has only a single pair of poles N and S, in which event it may be preferable to provide a balance B' for the rotor and surrounding the rotor are provided separate control coils CC for each engine cylinder, and the coils are adapted to be connected by the leads A and B to a separate circuit such as shown in FIG. 3 and consisting of a separate transformer TR and power transistor T_1 and triggering transistor T_2 for each control coil CC. All of the systems are connected to a single battery or D.C. power source. In this form, the pulse generator PG serves to trigger the transistors.

The systems of FIGS. 1 and 2 are compatible and the operation of the form of FIG. 2 is the same as explained above.

In the circuit shown in FIG. 3, there is shown a variable resistor in the collector C_1 circuit of transistor T_1 . This is provided as an adjustment for the energy level of the system by being able to control the flow of current. This is an additional feature which has a limit because reducing the energy too much will create a reduction in output voltage.

FIG. 4 shows a practical adaptation of a low tension system such as shown diagrammatically in FIG. 2.

FIG. 5 illustrates a practical adaptation of the system shown schematically in FIG. 1 and in this system the magnetic rotor PG may be provided with pole shoes in the form of a soft iron castings G which are formed separately and are then positioned over rotor PG and secured thereto by any suitable means, such as press fit or by soldering, welding or other suitable means. The castings G have the pole shoes N and S integral therewith and it is only necessary to properly orient the castings G on the rotor PG with the pole shoes in proper relation.

It has been found that in a twelve-volt ignition system with a twelve-volt battery D.C. that the components may have the following characteristics:

Transistor T_1 —10 amp. power transistor
 Transistor T_2 —2 amp. power transistor
 Control coil—300 turns of No. 27 wire
 Secondary—wound in 15 sections with 30,000 turns of No. 42 wire
 Primary—50 turns of No. 18 wire

$$\text{Ratio of } P \text{ to } S = \frac{50}{30,000} = \frac{1}{600}$$

Z_1 —10 volt zener diode
 Permanent magnet rotor PG—Alnico V

According to this system, the transistor along with the permanent magnet type pulse generator replaces the contacts and condenser used in present battery type spark ignition engines. It provides maintenance-free ignition for the engine along with high performance. The small pulse type generator induces a voltage in the triggering transistor which causes this transistor to conduct. This is accomplished each time a pair of poles sweep by a control coil located in the emitter to base circuit of the transistor. This causes the main power transistor to conduct by letting its base circuit conduct. This main power transistor is non-conductive when its base circuit is open. This offers a "make" type of arrangement in the system. During this "make" type of arrangement, the collector circuit in series with the primary is subjected to a transient pulse of current which causes a transient voltage according to Faraday's law. The time constant of this pulse is limited only by the pulse generator control coil and

the primary winding since the time response of the transistors is a great deal faster. This transient voltage is then transformed to the secondary and appears across the spark plug electrodes causing the spark plug to fire.

5 Since the rotor of the pulse generator is geared directly to the engine and is physically set in time phase with the distributor, the timing is preset and will follow the engine speed without any need for adjustment.

It will be seen that the foregoing ignition system inherently possesses certain advantages, such as greatly increasing spark plug life due to the reduction of multiple sparking or firing, which is inherently reduced by this system.

Furthermore, with the present system constant output 15 voltage is obtained over the entire engine speed range, thus making it possible to obtain better efficiency at higher speeds, which is the opposite to conventional systems.

Another advantage of the present system is that it is a 20 "make" type of circuit and it draws energy from the battery only when the circuit is conductive, thus drawing less current from the battery.

From the foregoing it will be seen that I have provided 25 new and improved means for obtaining all of the objects and advantages of the invention.

I claim:

1. In an ignition system for an internal combustion engine, a pulse generator having a rotor having north and south poles, coil means adjacent the periphery of said 30 rotor and adapted to have a pulse induced therein by said poles of said rotor upon relative rotation of said rotor and coil means, a source of direct current, a transistor switching circuit connected to said coil means and to said source of current, transformer means having a sectional 35 wound secondary, said transformer means being connected to said source of current through said switching circuit, said transistor switching circuit comprising a cascaded transistor switching arrangement, whereby said pulse generator produces a pulse in said transistor circuit 40 causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

2. In an ignition system for an internal combustion engine, a pulse generator having a rotor having a plurality of spaced pairs of poles, one of said pairs of poles being utilized for each engine cylinder, a coil adjacent the periphery of said rotor and adapted to have a pulse induced therein by each of said pairs of poles upon relative rotation of said coil and said pairs of poles, a distributor arm operatively connected to said rotor and adapted to be rotated upon rotation of said rotor, a plurality of contacts, 50 one of said contacts being provided for each pair of poles, each of said contacts being adapted to be connected to a respective ignition means for igniting a charge in a respective engine cylinder, a source of direct current, a transformer, the high tension side of said transformer being electrically connected to said distributor arm, a cascaded transistor switching arrangement directly coupled to said coil and adapted to connect said source of current to said transformer said coil being connected to one of said transistors, said transistor having its base and emitter electrodes in series between the base electrode and ground, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

3. In an ignition system for an internal combustion engine, a pulse generator having a rotor having a plurality

of spaced pairs of poles, one of said pairs of poles being utilized for each engine cylinder, a coil adjacent the periphery of said rotor and adapted to have a pulse induced therein by each of said pairs of poles upon relative rotation of said coil and said pairs of poles, a distributor arm operatively connected to said rotor and adapted to be rotated upon rotation of said rotor, a plurality of contacts, one of said contacts being provided for each pair of poles, each of said contacts being adapted to be connected to a respective ignition means for igniting a charge in a respective engine cylinder, a source of direct current, a transformer the high tension side of said transformer being electrically connected to said distributor arm, a cascaded transistor switching arrangement adapted to connect said source of current to said transformer, said coil being connected to one of said transistors, said transistor having its base and emitter electrodes in series between the base electrode and ground, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage, said transformer having a sectional wound secondary to reduce capacitance due to proximity of secondary windings.

4. In an ignition system for an internal combustion engine, a pulse generator having a rotor having a plurality of spaced pairs of poles, one of said pairs of poles being provided for each engine cylinder, a coil adjacent the periphery of said rotor and adapted to have a pulse induced therein by each of said pairs of poles upon relative rotation of said coil and said pairs of poles, distributor means operatively connected to said rotor and adapted to be rotated upon rotation of said rotor, a plurality of spaced contacts, one of said contacts being provided for each engine cylinder and being connected to an ignition means for said cylinder, a source of direct current, a transformer connected to said distributor means for supplying energy thereto, said source of current being connected to said transformer through a cascaded semiconductor switching arrangement, said transformer having a sectional wound secondary to reduce capacitance due to proximity of secondary windings.

5. In an ignition system for an internal combustion engine, a pulse generator having a rotor having north and south poles, coil means adjacent the periphery of said rotor and adapted to have a pulse induced therein by said poles of said rotor upon relative rotation of said rotor and coil means, a source of direct current, a transistor switching circuit for each engine cylinder and connected to a respective coil means and to said source of current, transformer means connected to said source of current through said switching circuit, said transformer having a sectional wound secondary, said transistor switching circuit comprising a cascaded transistor switching arrangement, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

6. In an ignition system for an internal combustion engine, a pulse generator having a rotor having north and south poles, coil means adjacent the periphery of said rotor and adapted to have a pulse induced therein by said poles of said rotor upon relative rotation of said rotor and coil means, a source of direct current, a transistor switching circuit for each engine cylinder and connected to a respective coil means and to said source of current, transformer means connected to said source of current through said switching circuit, said transformer having a

pi wound secondary, said transistor switching circuit comprising a cascaded transistor switching arrangement, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

7. In an ignition system for an internal combustion engine, a pulse generator having a rotor having a plurality of spaced pairs of poles, one of said pairs of poles being utilized for each engine cylinder, a coil adjacent the periphery of said rotor and adapted to have a pulse induced therein by each of said pairs of poles upon relative rotation of said coil and said pairs of poles, a distributor arm operatively connected to said rotor and adapted to be rotated upon rotation of said rotor, a plurality of contacts, one of said contacts being provided for each pair of poles, each of said contacts being adapted to be connected to a respective ignition means for igniting a charge in a respective engine cylinder, a source of direct current, a transformer, the high tension side of said transformer being electrically connected to said distributor arm, said transformer having a sectional wound secondary, a cascaded transistor switching arrangement adapted to connect said source of current to said transformer, said coil being connected to one of said transistors, said transistor having its base and emitter electrodes in series between the base electrode and ground, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

8. In an ignition system for an internal combustion engine, a pulse generator having a rotor having a plurality of spaced pairs of poles, one of said pairs of poles being provided for each engine cylinder, a coil adjacent the periphery of said rotor and adapted to have a pulse induced therein by each of said pairs of poles upon relative rotation of said coil and said pairs of poles, a distributor arm operatively connected to said rotor and adapted to be rotated upon rotation of said rotor, a plurality of contacts, one of said contacts being provided for each pair of poles, each of said contacts being adapted to be connected to a respective ignition means for igniting a charge in a respective engine cylinder, a source of direct current, a transformer, the high tension side of said transformer being electrically connected to said distributor arm, said transformer having a pi wound secondary, a cascaded transistor switching arrangement adapted to connect said source of current to said transformer, said coil being connected to one of said transistors, said transistor having its base and emitter electrodes in series between the base electrode and ground, whereby said pulse generator produces a pulse in said transistor circuit causing the transistors of said transistor circuit to conduct and allow a flux field to be built up in the primary of said transformer for a predetermined time whereupon flow of current will be terminated and flux field will collapse inducing a voltage which will be transformed by said transformer and provide the desired ignition voltage.

9. In an ignition system for an internal combustion engine, a pulse generator having a rotor having a pair of north and south poles, a plurality of coil means adjacent the periphery of said rotor and adapted to have a pulse induced therein by said poles of said rotor upon relative rotation of said rotor and coil means, each of said coil means being adapted to be connected to the igniting means of the internal combustion engine, a source of direct current, a transistor switching circuit for each

engine cylinder and connected to a respective coil means and to said source of current, and transformer means for each of said coil means connected to said source of current through said switching circuit for each respective coil means.

10. In an ignition system for an internal combustion engine, a pulse generator having a rotor having a pair of north and south poles, a plurality of coil means adjacent the periphery of said rotor and adapted to have a pulse induced therein by said poles of said rotor upon relative rotation of said rotor and coil means, each of said coil means being adapted to be connected to the igniting means of the internal combustion engine, a source of direct current, a transistor switching circuit for each engine cylinder and connected to a respective coil means 15 and to said source of current, and transformer means for each of said coil means connected to said source of current through said switching circuit for each respective coil means, said transistor switching circuits each comprising a cascaded transistor switching arrangement.

11. In an ignition system for an internal combustion engine, a pulse generator having a rotor having a plurality of spaced pairs of poles, one of said pairs of poles being utilized for each engine cylinder, a coil adjacent the periphery of said rotor and adapted to have a pulse induced therein by each of said pairs of poles upon relative rotation of said coil and said pairs of poles, a distributor arm operatively connected to said rotor and 20

adapted to be rotated upon rotation of said rotor, a plurality of contacts, one of said contacts being provided for each pair of poles, each of said contacts being adapted to be connected to respective ignition means for igniting 5 a charge in a respective engine cylinder, a source of direct current, a transformer, the high tension side of said transformer being electrically connected to said distributor arm, a cascaded transistor switching arrangement directly coupled to said coil and adapted to connect said source of current to said transformer, said coil being connected to one of said transistors.
